US0D1082843S

(12) **United States Design Patent** (10) **Patent No.:** **US D1,082,843 S**
Andrich et al. (45) **Date of Patent:** **** Jul. 8, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Brian James Andrich**, San Francisco, CA (US); **YunJae Kim**, Sunnyvale, CA (US)

(73) Assignee: **Apple Inc.**, Cupertino, CA (US)

(**) Term: **15 Years**

(21) Appl. No.: **29/953,361**

(22) Filed: **Jul. 22, 2024**

Related U.S. Application Data

(63) Continuation of application No. 29/892,071, filed on May 12, 2023, now Pat. No. Des. 1,036,502, which is (Continued)

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.

1 Claim, 2 Drawing Sheets
(1 of 2 Drawing Sheet(s) Filed in Color)

Related U.S. Application Data

a continuation of application No. 29/834,633, filed on Apr. 13, 2022, now Pat. No. Des. 990,515, which is a continuation of application No. 29/738,913, filed on Jun. 21, 2020, now Pat. No. Des. 949,185.
